UNITED STATES PATENT OFFICE.

THOMAS B. JACKSON, OF BELMONT, OHIO.

FIREPLACE-HEATER.

SPECIFICATION forming part of Letters Patent No. 694,155, dated February 25, 1902.

Application filed June 12, 1901. Serial No. 64,292. (No model.)

To all whom it may concern:

Be it known that I, THOMAS B. JACKSON, a citizen of the United States, residing at Belmont, in the county of Belmont and State of Ohio, have invented certain new and useful Improvements in Fireplace-Heaters; and I do hereby declare the following to be a full, clear, and exact description of the invention, such as will enable others skilled in the art to which it appertains to make and use the same..

My invention relates to improvements in fireplace-heaters, and more particularly to a form of heater adapted to heat by direct radiation, hot air, and by hot water.

The object of the present invention is the production of a heater which shall produce a maximum of heat by the use of a minimum of fuel, the same being accomplished by means of the greatest possible exposure of heating-surface.

With this and other objects in view it consists of certain novel constructions, combinations, and arrangements of parts, as will be hereinafter fully described and claimed.

In the accompanying drawings, Figure 1 represents a front elevation of a heater embodying the features of the present invention. Fig. 2 represents a similar view of the same, the double doors being swung back to disclose the interior structure. Fig. 3 represents a transverse vertical section on line 3 3 of Fig. 1. Fig. 4 represents a longitudinal vertical section on line 4 4 of Fig. 3, and Fig. 5 represents a horizontal section on line 5 5 of Fig. 3.

In the construction of heaters it has been found most desirable to expose the greatest possible surface to the action of the products of combustion, and in order to accomplish this I contemplate providing means for direct radiation which is adapted for heating the surrounding atmosphere by hot water and by hot air, either of which may be utilized at a greater or less distance from the heater, as may be desired.

In carrying my invention into practice, as illustrated in the accompanying drawings, I provide a suitable casing, within which is situated the usual fire-box 1, provided with a grate 2, preferably of the basket type. The front part of the grate is preferably hinged, as at 3, to a flange 4, resting upon lugs 5, and its rear part is provided with hooks 5, which

engage supporting rods or lugs 6. Beneath the grate is situated a hopper-shaped ash-pan 7, provided with side flanges 8, adapted to slide in ways 9, formed on the side partition-walls 11 and 12 and the rear partition-wall 10. The bottom of the ash-pan is provided with a suitable aperture 13, adapted to be closed by a suitable slide 14. The slide 14 is provided with a suitable handle 14' for reciprocating it and with a lug 14'' for limiting its movement. An aperture 15, formed in the slide, is adapted to register when said slide is moved forward with aperture 13 to permit the ashes to be discharged from the ash-pan to the cellar, if desired.

The detachable fender-base of the heater is provided with a suitable slide-valve 16, preferably at the front thereof, for permitting the admission of air to the fire-box, and said valve may be provided with any suitable operating-handle 16'.

The products of combustion are conducted from the fire-box through a passage 17 to the smoke-stack or other outlet, (not shown,) said passage being provided with a suitable damper 18, if desired.

The front of the heater is preferably provided with a plurality of double doors 19 and 20, which are adapted to be swung open to permit access to the interior of the heater. Each of the doors 19 is composed of two smaller doors hinged together, one of said doors being hinged to the front wall of the heater and the other provided with securing means at its free edge adapted to engage securing means carried by its corresponding double door, whereby the said doors may be secured together when closed and disengaged when it is desired to open them.

Surrounding the fire-box on three sides thereof is a hot-air chamber 21, said chamber being formed by the walls of the casing and the partition-walls 10 11 12. Air from any suitable source of supply may be admitted to the chamber 21 through a pipe 22. Arranged above the fire-box is a superheating-chamber 22', which communicates with the chamber 21 and with a vertical hot-air chamber 23. Situated above the superheating-chamber 22', so as to form the smoke-passage 17, is a second superheating-chamber 24, which communicates with the vertical chamber 23 and with

a second vertical chamber 25. The chamber 25 is provided with a pipe 26 or other suitable conduit for the purpose of conducting heat to suitable registers arranged at any 5 desired distance from the heater. Suitable valves 27 27 may also be provided for supplying cool air, taken at the front of the heater, to the chamber 21.

The numeral 28 indicates a hot-water heater 10 detachably arranged immediately beneath the chamber 22' and in the upper part of the firebox. The water-heater is supported upon cleats *a*, secured to the side and rear walls of the casing, and is provided with a pipe 29 for 15 supplying water thereto and with a pipe 30 for conducting hot water to radiators or other heating devices. The conduit 30 may be provided with a suitable valve 31 for the removal 20 of dirt or other foreign matter from the water-heater 26 when desired.

A register 32, operated by a suitable handle 33, may be provided in the front wall of the heater to supply heated air to the apartment in which the heater is situated. Of 25 course it will be understood that a certain amount of heat will be radiated directly from the heater, but by the provision of the register 32 the temperature in the apartment may be materially raised when desired.

30 Although I have described in detail the various features of my invention, yet I do not wish to be understood as being limited to the exact construction described, as I may alter or change the shape, size, and minor details 35 of construction without departing from the spirit and scope of the present invention.

Having thus fully described my invention, what I claim as new, and desire to secure by Letters Patent, is—

40 1. In a fireplace-heater, the combination with the fire-box of a hot-air chamber par-

tially surrounding the same, two superheating-chambers arranged one above the other, a combustion-passage between the same, said superheating-chambers being in communication with each other and the lower one in communication with the hot-air chamber, and a vertical chamber in communication with the upper superheating-chamber, substantially as specified. 45

2. In a fireplace-heater, the combination with the fire-box, of a hot-air chamber partially surrounding the same, superheating-chambers arranged above the hot-air chamber so as to form a passage for the products 50 of combustion, the lower superheating-chamber being in communication with the hot-air chamber, and two oppositely-arranged vertical chambers, one of said chambers being in communication with both superheating-chambers, and the other in communication with the upper superheating-chamber, substantially as specified. 55

3. In a fireplace-heater, the combination with the fire-box, a hot-air chamber partially 60 surrounding the same, two superheating-chambers arranged one above the other, said superheating-chambers being in communication with each other and the lower one in communication with the hot-air chamber, a combustion-passage between the superheating-chambers, and a vertical chamber in communication with the upper superheating-chamber, of a detachably-arranged water-heater 70 situated in the upper part of the fire-box and beneath one of the superheating-chambers, substantially as specified. 75

THOMAS B. JACKSON.
